ATTACHMENT FOR MELTING FURNACES

Carl Albert Barlow, Wabash, Ind., assignor to
American Rock Wool Corporation, Wabash,
Ind., a corporation of Indiana

Application September 1, 1937, Serial No. 162,010

7 Claims. (Cl. 266—38)

This invention relates generally to improvements in apparatus for the manufacture of mineral wool and more particularly to an improved apparatus associated with a furnace or cupola in which the raw materials are melted for deflecting and dividing the stream of lava or molten materials flowing from the furnace into a plurality of smaller streams prior to being shredded into fibers by the engagement therewith of a jet 5 of air or steam.

An object of the present invention is to provide an improved and novel apparatus for dividing a stream of molten materials flowing from a furnace into smaller streams of substantially 10 equal size.

A further object of the present invention is to provide an improved and novel apparatus for dividing a stream of molten materials flowing from a furnace into a plurality of smaller streams 15 and for varying the relative sizes of the smaller streams.

Another object of the present invention is to provide an improved and novel apparatus for dividing a stream of molten materials flowing from 20 a furnace into a plurality of smaller streams, which may be quickly and easily adjusted relatively to the stream from the furnace for varying the relative sizes of the smaller streams.

A further object is to provide an improved 25 and novel structure for the purposes above referred to, which may be quickly and easily attached to or detached from the furnace, and in which the several parts may be readily replaced.

Other objects and advantages will be apparent 30 from the following description.

In the drawings illustrating the invention:

Figure 1 is a fragmentary front elevation of 35 a furnace or cupola showing the present invention as applied thereto;

Figure 2 is a side elevation of one of the supporting members which is adapted for being connected with the furnace, and comprises a part 40 of the present invention;

Figure 3 is a sectional view taken along the line 3—3 of Figure 5;

Figure 4 is a side elevation of the angle member which is adapted for being detachably connected with the structure shown in Figure 3;

Figure 5 is a vertical sectional view taken substantially along the line 5—5 of Figure 1;

Figure 6 is a vertical sectional view taken substantially along the line 6—6 of Figure 1;

Figure 7 is a fragmentary front elevation of a

furnace illustrating another embodiment of the invention; and

Figures 8 and 9 are side elevations of members of the structure shown in Figure 7, certain elements associated therewith being shown in 5 section.

In the embodiment selected to illustrate the invention, a conventional furnace or cupola 10 is employed for melting the raw materials, and sets 10 on a base 12 which is provided with supporting legs 14. The front of the furnace 10 is provided with an opening 16 which extends to the bottom of the furnace and is filled with any suitable refractory material 18, such as refractory brick 35 or clay.

The refractory material forms a projecting portion 20 from the front of the furnace and is provided with a passageway 22 therethrough in communication with the interior of the furnace, through which the molten material or lava flows 20 from the furnace.

An anchor bar or strip 24 is positioned on the front of the furnace beneath the refractory projection 20, as shown in Figures 1, 5, and 6, and may be connected to the furnace or supported 25 by upright members 26 mounted on the base 12 as shown in Figures 1 and 6.

A pair of spaced-apart stationary or supporting plate members 28, as shown in Figures 1 and 2, and 5, are disposed at the opposite sides 30 of the opening 16 in the furnace, at the bottom thereof. Each of the supporting members 28 has an outwardly extending top flange portion 30 connected with the anchor bar 24 by any suitable means such as bolts for fixedly retaining the 35 members 28 in position.

Each of the plate members 28 is also provided with a projecting portion 32 continuous therewith which extends within the opening 16 between the adjacent side of the opening 16 and 40 the refractory filler contained therein which gives added rigidity to the plate members.

Each of the plate members 28 is further provided with an internal formation 34 which bears 45 on the front surface of the lower part of the refractory filling material and serves to aid in more firmly retaining the plate member 28 in the proper position relatively to the furnace.

The body portions of the spaced plate members 28 are provided with a plurality of slotted openings 36, 38, and 40, which are continuous with, and are inclined downwardly from the front edges of the plate members. Guide members or rods 42 and 44 are disposed in the aligned openings 36 and 38, respectively, of the spaced plate 50 55

- members 28 and are provided with nuts or head portions on the ends thereof in order that the cross-rod will not slide longitudinally out of the openings. It will be noted that the distance 5 between the heads of the rods is greater than the overall distance between the plate members 28 in order that the rods may be quickly and easily moved transversely out of the openings 36 and 38.
- 10 A movable member 46 is slidably disposed on the cross-rods 42 and 44, between the plate members 28, and is provided with elongated openings for receiving the cross-rods.
- 15 A shelf 48 positioned in an upwardly inclined plane toward the furnace is fixedly connected to the movable member 46 by any suitable means such as by a connecting member 50 which may be welded or otherwise secured to both the movable member 46 and the shelf 48.
- 20 An angle member, deflecting member, or open end trough 52 is mounted on the shelf 48, and is detachably connected therewith by means of a pair of spaced studs 54 which are connected with the trough 52 and extend through corresponding inverted T-shaped openings 56 in the shelf 48.
- 25 The shelf 48 is adapted for supporting the trough 52 in a position beneath the exterior opening of the passageway 22, whereby the molten material or lava which flows from the furnace 30 through the passageway 22 may drop on the trough and be divided into smaller streams of lava which flow from the opposite ends of the trough.
- 35 Each of the smaller streams of molten materials flowing from the ends of the trough 52 falls on a jet or blast of high pressure air or steam escaping from nozzles or blow-caps 58 and is shredded into very fine fibers known as mineral wool.
- 40 It has been found that the mineral wool obtained by the shredding of a small stream has finer fibers, and, consequently, is of better quality than that obtained by the shredding of a relatively large stream.
- 45 When the large stream of molten material strikes the shelf it normally divides into two smaller streams of material.
- 50 In practice, however, and during the continuous operation of the furnace, the molten material gradually accumulates on the trough 52 as a solid, due to the wide temperature difference between the molten material and the trough. This condition requires the frequent adjustment of the trough relatively to the original lava stream, 55 either by sliding the movable member 46 on the guide bars 42, or by tilting the trough 52, in order to control the flow of the smaller streams and keep them substantially equal in size. The positioning of the trough 52 compensates for the 60 obstructions deposited thereon by the molten material.
- 65 In order to manipulate and properly position the trough 52, a manually operable actuating rod 60 has one end fixedly connected with the movable member 46 and the other end provided with a handle.
- 70 The actuating rod 60 slidably extends through the slotted opening 40 of one of the plate members 28, and is retained in the desired vertical position by being removably disposed in one of several closely positioned slotted openings 62 in a retaining member 64 which is in the nature of an upright angle bar attached to the supporting base 12.

From the above description it will be noted that

the trough 52 may be disposed in the desired position beneath the original lava stream by sliding the actuating rod 60 through the slotted opening 40 in the plate member 28, or may be disposed and retained in the required tilted position by raising or lowering the actuating rod 60 and placing in the proper slotted opening 62 in the retaining member 64.

It will be noted that the inner ends of the slotted openings 36, 38, and 40 are elongated vertically, 10 which, together with the elongated openings in the movable member 46 through which the guide rods 42 and 44 extend provides for the inclination of the trough 52 and the actuating rod 60 within the required limits.

When it is necessary or desirable to remove the material deposited on the trough 52, the trough may be tilted and retained in position for directing the large stream of lava away from the deposit and the deposit may be loosened from the 20 trough with a hammer and chisel bar.

During the loosening of the deposit, the studs 54 of the trough 52 are driven to the ends of the lateral portions of the T-shaped openings 56 in the shelf 48, and prevent the trough from jumping or being disconnected from the shelf. Should the trough be burned through or deformed from continuous use, however, the guide bars 42 and 44, together with the actuating rod 60, may be lifted through the slotted openings 36, 38 and 40, 30 of the plate members 28, for disconnecting the movable member 46, the shelf 48, and trough 52 from the furnace, after which the trough or other parts may be quickly and easily replaced, and again operatively connected with the furnace. 35

The blow caps 58 for directing the blasts of steam or air against the streams of molten materials are operable for being disposed in the desired positions relatively to the streams of molten material.

The mechanism for controlling the operation of the blow caps 58, however, does not comprise a part of the present invention, and, therefore, no further description in this regard is believed to be necessary.

Another embodiment of the invention is illustrated in Figures 7 to 9, inclusive, in which parts corresponding to those hereinbefore described have been given identical reference characters.

As shown in Figure 7, a pair of guide members 70 have ends fixedly connected with the movable member 46 and extend through openings 72 in a plate member 74 which is otherwise similar to the plate members 28. The actuating member 60 has an end fixedly connected with the movable member 46 and extends through an opening 76 in a plate member 78 which is otherwise similar to the plate member 74. The actuating member 60 is operatively associated with a retaining member 64, as herein described, which is not illustrated in Figure 7.

The openings 72 and 76 in the plate members for receiving the guide members 70 and the actuating member 60, respectively, are preferably L-shaped slotted openings disposed in the positions shown in Figures 8 and 9, and provide for the adjustability of the angle shaped trough 52 relatively to the molten stream flowing from the opening 22 in the furnace 10. The slotted openings 70 also provide for the guide members 70 and the actuating member 60 together with the associated structure, being quickly and easily disconnected from the supporting members 74 and 78.

From the above description it will be observed 75

that a mechanism is provided which accomplishes the objectives hereinbefore set forth.

Modifications and changes may be made without departing from the spirit of the invention, 5 and it is intended that this invention shall be limited only by the scope of the appended claims.

I claim:

1. In combination with a furnace for melting materials and having an outlet opening through 10 which a stream of the molten materials may flow, of means for deflecting and dividing the molten stream comprising a pair of bracket plates connected to the furnace and positioned on opposite sides of the opening, supporting rods carried by the bracket plates, a carriage mounted on the supporting rods and positioned between the bracket plates below the outlet opening for intercepting a vertical molten stream flowing from the outlet opening in the furnace, said carriage being movable between the bracket plates transversely to the vertical molten stream, one of said 15 supporting rods being connected to the carriage and operable for adjustably positioning the carriage relatively to the molten stream.

2. In combination with a furnace for melting materials and having an outlet opening through 20 which a stream of the molten materials may flow, of means for deflecting and dividing the molten stream comprising a pair of bracket plates connected to the furnace and positioned on opposite 25 sides of the opening, supporting rods carried by the bracket plates, said bracket plates being provided with downwardly extending slotted openings continuous with the front edge thereof for receiving the supporting rods, a carriage mounted on the supporting rods and positioned between the bracket plates below the outlet opening for intercepting a vertical molten stream flowing from the outlet opening in the furnace, said 30 carriage being movable between the bracket plates transversely to the vertical molten stream, one of said supporting rods being connected to the carriage and operable for adjustably positioning the carriage relatively to the molten stream.

3. In combination with a furnace for melting materials and having an outlet opening through 35 which a stream of the molten materials may flow, of means for deflecting and dividing the molten stream comprising a pair of bracket plates connected to the furnace and positioned on opposite sides of the opening, a pair of spaced apart supporting rods carried by the bracket plates and positioned one above the other, a carriage mounted on the supporting rods and positioned between the bracket plates below the outlet opening for intercepting a molten stream flowing vertically 40 from the outlet opening, said carriage being movable transversely to the molten stream, and an actuating rod fixedly connected to the carriage 45 and associated with one of the bracket plates for adjustably positioning the carriage relatively to the molten stream.

4. In combination with a furnace for melting materials and having an outlet opening through 50 which a stream of the molten materials may flow, of means for deflecting and dividing the molten stream comprising a pair of bracket plates connected to the furnace and positioned on opposite sides of the opening, a pair of spaced apart supporting rods carried by the bracket plates and positioned one above the other, a carriage mounted on the supporting rods and positioned between the bracket plates and below the outlet opening in the furnace for intercepting a stream 55 of molten material flowing vertically from the

outlet opening, said carriage being movable transversely to the molten stream and comprising a member positioned vertically for receiving the supporting rods, a shelf fixedly connected to said member, a trough mounted on the shelf and provided with open ends, and an actuating rod connected with the upright member for adjustably positioning the trough relatively to the molten stream. 5

5. In combination with a furnace for melting 10 materials and having an outlet opening through which a stream of the molten material may flow, of means for deflecting and dividing the molten stream comprising a pair of bracket plates connected to the furnace and positioned on opposite 15 sides of the opening, a pair of supporting rods carried by the bracket plates and disposed in spaced apart, substantially horizontal positions, one above the other, said bracket plates being provided with corresponding slotted openings extending 20 downwardly from the front edge thereof for receiving the supporting rods, a carriage mounted on the supporting rods and positioned between the bracket plates and below the outlet opening for intercepting a vertical molten stream 25 flowing from the outlet opening, said carriage comprising an upright member provided with slotted openings for receiving the supporting rods, a trough having open ends carried by the upright member, and an actuating rod connected to the 30 upright member for moving the trough transversely to the molten stream and for tilting the trough relatively to the molten stream.

6. In combination with a furnace for melting materials and having an outlet opening through 35 which a stream of the molten materials may flow, of means for deflecting and dividing the molten stream comprising a pair of bracket plates connected to the furnace and positioned on opposite sides of the opening a pair of supporting rods carried by the bracket plates and disposed in spaced apart, substantially horizontal positions, one above the other, said bracket plates being provided with corresponding slotted openings extending 40 downwardly from the front edge thereof for receiving the supporting rods, a carriage mounted on the supporting rods and positioned between the bracket plates and below the outlet opening for intercepting a vertical molten stream flowing from the outlet opening, said carriage comprising 45 an upright member provided with slotted openings for receiving the supporting rods, a trough having open ends carried by the upright member, an actuating rod connected to the upright member for moving the trough transversely to the 50 molten stream and for tilting the trough relatively to the molten stream, and a bracket connected to the furnace and provided with a series of notches therein for receiving the actuating rod whereby the trough may be retained in the desired 55 tilted position with respect to the molten stream. 60

7. In combination with a furnace for melting materials and having an outlet opening through 65 which a stream of the molten materials may flow, of means for deflecting and dividing the molten stream comprising a pair of bracket plates connected to the furnace and positioned on opposite sides of the opening, a carriage positioned between the bracket plates and below the outlet opening in the furnace and comprising an upright member, an open-end trough carried by the upright member for intercepting a vertical stream 70 of molten material flowing from the outlet open- 75

5 ing in the furnace, means for supporting the carriage comprising a pair of spaced apart rods horizontally positioned one above the other and fixedly connected to the upright member and receivable in slotted recesses in one of the bracket plates, and an actuating rod having one end connected with the upright member and extend-

ing through a slotted recess in the other bracket plate, said actuating rod being operable for moving the trough transversely to the stream of molten materials and for tilting said trough relatively to said stream of molten materials.

CARL ALBERT BARLOW.
